UNITED STATES PATENT OFFICE

136,445

DESIGN FOR A CARVING KNIFE

Joseph R. Gerber, Portland, Oreg.

Application May 18, 1943, Serial No. 110,229

Term of patent 14 years

To all whom it may concern:

Be it known that I, Joseph R. Gerber, a citizen of the United States, residing at Portland, county of Multnomah, State of Oregon, have invented a new, original, and ornamental Design for Carving Knives, of which the following is a specification, reference being had to the accompanying drawing, forming part thereof.

Fig. 1 is a side elevational view of a carving knife showing my new design.

Fig. 2 is a fragmentary bottom view taken along the line 2—2 in Fig. 1.

Fig. 3 is an end elevation taken along the line 3—3 in Fig. 1.

I claim:

The ornamental design for a carving knife, as shown.

JOSEPH R. GERBER.
